UNITED STATES PATENT OFFICE

HARRY C. GAMMETER, OF CLEVELAND HEIGHTS, OHIO

SIGN

Application filed October 7, 1927. Serial No. 224,540.

- This invention pertains to signs that are adapted for use as outdoor advertising devices, markers for parks and institutions, and other similar displays.
- 5 The primary purpose of the invention is to produce a device of the above mentioned character that is artistic, neat and attractive of appearance and, therefore, not open to the objections urged against the ordinary type of sign boards.
- 10 Another object is to produce devices of the foregoing nature having removable panels on which the matter to be displayed is painted or to which it is otherwise applied. This construction permits the signs to be easily and quickly changed from time to time, enables the sign bearing panels to be painted or otherwise produced in a shop and taken to the display locations where they are inserted in the frames of the devices, and allows the same signs to be interchanged among several devices.
- 15 In line with the immediately foregoing is the further object of constructing the device with a stationary or permanent panel to one or both sides of which the portable or removable panel or panels is or are applied and which may bear on one or both of its faces suitable indicia, such as an advertisement for the rental of the space unoccupied by a portable panel. Obviously, where the sign is of a permanent nature, as when used to designate parks or the like, the removable panels 20 are omitted and the matter to be displayed is placed directly upon the stationary panel.
- 25 Other objects are to provide a relatively simple and inexpensive but substantial and durable construction by the nature of which the erection of the sign is facilitated, and the emplacing or changing of the portable panels expedited.
- 30 The objects above enumerated with others hereinafter appearing are attained in the construction illustrated in the accompanying drawings wherein Fig. 1 is a perspective view of my improved display device or sign; Fig. 2 is a fragmentary front elevation of the same with parts broken away to reveal certain structural features; Fig. 3 is a vertical sec-
- tion through the device, the plane of section being indicated by the line 3—3 of Fig. 2, while Figs. 4 and 5 are sectional details, on a somewhat larger scale, on the respective lines 4—4 and 5—5 of Fig. 2.
- 35 The device is made up of two major units, namely, a supporting structure, and a frame sustained thereby. The supporting structure comprises uprights 1 to the upper ends of which is applied a horizontal cross member 2. Supported by and between the uprights a suitable distance below the cross member 2, and parallel therewith, is a cross member 3.
- 40 The present embodiment is of rustic design, the uprights and cross members being formed of timbers, and as a convenient means of connecting the parts together, the upper ends of the uprights and the ends of the cross member 3 are shaped to provide tenons 4 that are fitted into grooves or notches in the cross member 2, and the uprights 1, respectively. Lag screws 5 are passed through the grooved or notched parts and are driven axially into the parts having the tenons, as shown in dotted lines in Fig. 2.
- 45 To enhance the artistic appearance of the structure, and for more practical purposes as will hereinafter appear, cross pieces 6 are applied to the top of the member 2 at equally spaced points throughout the length thereof, and surmounting said cross pieces are slabs 7. These slabs consist, preferably, of planks ripped from the sides of logs and on which the bark has been left so as to add to the rustic effect. Furthermore, this material can be procured very cheaply. These signs are intended for use especially in rural communities, along public highways, in gardens, parks, and such places, and it is proposed that shrubbery be grouped about the structure, and that vines be planted so as to climb the uprights and intertwine the top portion of the device, as suggested in Fig. 1, so that the beauty of the ensemble will increase with age.
- 50 The cross members 6 and slabs 7 form an arbor for the vines, and they have a further purpose of providing a support for electric lights for illuminating the signs, where such is desirable and where current is available.

Supported by and between the cross members 2 and 3 is the sign proper that is designated generally by the reference numeral 10. As best shown in Figs. 4 and 5, the same is made up of a sheet 11 of metal or other material, and to the opposite sides of the edge portion of said sheet are applied frame members 12 which, in the present instance, consist of boards on which the bark has been left so as to harmonize with the remainder of the structure. The inner edges of the frame members 12 adjacent the sheet 11 are rabbed, as indicated at 13. At suitable points, the adjacent faces of the top and bottom frame members are grooved to receive hangers 14, and each of these is preferably formed of a piece of strap metal that is bent at its middle upon itself and turned outwardly at its ends to provide feet 15 which are accommodated by recesses cut in the inner edges of the frame members. The edges of the sheet 11 are inserted between the branches of the hangers, and bolts 16 are then inserted through aligning holes in the frame members 15 and hangers, the inner one of the two bolts associated with each hanger passing also through the marginal portion of the sheet 11. The frame members are counterbored to accommodate the heads and nuts of the bolts 16, and these counterbores are preferably plugged so as to conceal the bolts and nuts, as shown in detail in Fig. 5. It will be understood that the end members of the frame are secured together and to the sheet 11 in a similar manner. The hangers 14 have slots 18 through which hooks 19 are adapted to be engaged, and the shanks of these hooks pass through vertical holes in the cross members 2 and 3 and are shown as having washers 40 and nuts applied to their threaded end. When the parts are in normal condition the hangers 14 are prevented from being disengaged from the hooks 19 because of the return bent ends of the hooks, and when it is desired to remove the frame, the nuts are relaxed to allow the hooks to be moved inwardly so that the hangers may be removed laterally from the hooks.

As previously stated, if the matter of the sign or display is to be of a permanent nature it is painted upon or otherwise applied to one or both sides of the sheet 11 (whether one or both sides are used depending upon the location of the structure), but if the signs are to be changed from time to time a removable panel or panels is or are set within the openings of the frame on one or both sides of the sheet 11.

Each panel, designated generally by the reference numeral 20, is composed of a frame 21, having cross members 22, and a sheet 23 of metal or other appropriate material that is attached by suitable means to the frame. To the rear side of the top member of each of the panel frames 21 are secured tongues 25 that

are adapted to be inserted within the rabbet 13 in the corresponding top frame member 12, and to the lower member of the frame 21, and to the end members if desired, are applied buttons 26 that are carried by studs 27 having grooved heads 28 that are accessible from the front side of the panel. The frame 21 is preferably cut away to accommodate the buttons and the tongues 25. By reason of the construction above described a panel 20 may be conveniently applied to each side of the sheet 11 by engaging the tongues 25 within the rabbet of the corresponding top frame member 12 and, after the panel is fully inserted within the opening of the frame comprised of the members 12, the buttons 26 are turned by means of a screw driver applied to the grooved heads 28 of the studs 27 so as to engage the ends of the buttons within the rabbets of the lower and end frame members 12.

Thus it will be seen that my invention provides a relatively simple and inexpensive sign structure that is artistic of appearance and which, by reason of its construction, enables the display to be easily and quickly changed. As previously stated, the sheet 11 may permanently bear matter of any desired character such, for example, as an advertisement for the rental of the space unoccupied by a removable panel, and the panels may be readily changed from time to time as it is desired to vary the advertisements displayed by the device.

Having thus described my invention, what I claim is:

1. In a device of the character set forth, the combination of a sheet of suitable material, frame members applied to opposite sides of the marginal portion of said sheet, hangers disposed between the opposed frame members and overlapping the edge of the sheet, fastening means extending through the frame members, hangers and sheet, and a supporting structure to which the hangers are connected.

2. In a device of the character set forth, the combination of a sheet of suitable material frame members applied to the opposed sides of the marginal portion of said sheet, hangers formed of metal straps bent approximately at their middles upon themselves and turned outwardly at their ends, said hangers being disposed between opposed members of the frame and having their ends arranged on opposite sides of the edge portion of the sheet, fastening means extending through the frame members, hangers and sheet, a supporting structure, and means connecting said hangers to said supporting structure.

3. A sign structure consisting of a flat sheet of material, wooden strips secured flatwise against the edge portions of said sheet and extending about the periphery of the same to form a frame, said strips being rab-

beted throughout their lengths along their inner edges adjacent the sheet and all being of substantially the same cross section, and a panel designed to fit within the frame against the sheet and having fixed tongues on one edge for engagement within the rabbet of the adjacent side of the frame, and movable fastening members adjacent other of its edges for engagement within the rabbets of the corresponding sides of the frame, the panel concealing the rabbets, tongues and fastening members when placed within the frame.

4. A sign structure consisting of a thin flat sheet of material, wooden strips applied to the opposite sides of the marginal portions of the sheet and projecting outwardly beyond the edges thereof so that the corresponding strips on opposite sides of the sheet contact with each other, the strips extending entirely about the periphery of the sheet to form a frame ad being rabbeted along their inner edges adjacent the sheet, all strips being of substantially the same cross section, and panels designed to fit within the openings of the frame on opposite sides of the sheet, each panel having fixed tongues on one edge for engagement within the rabbet of the adjacent side of the frame, and movable fastening members adjacent other of its edges for engagement within the rabbets of the corresponding sides of the frame, the panels concealing the rabbets, tongues and fastening members when placed within the frame.

In testimony whereof, I hereunto affix my signature.

HARRY C. GAMMETER.
